UNITED STATES PATENT OFFICE.

MARTIN THUM, OF ROCHESTER, NEW YORK.

FURNITURE.

Application filed June 17, 1926. Serial No. 116,744.

The present invention relates to furniture and more particularly to the type in which there is provided a bottom member movable to an inner position to provide a seat and to an outer position to provide part of a reclining portion. An object of this invention is to provide a novel extension for the bottom member for occupying the space between the bottom member and the back of the furniture when the bottom member is in its outer position. A further object of the invention is to provide in furniture of the type mentioned, a bottom member extension which is formed of sections foldably connected and automatically moved to operative position when the bottom member is moved to its outer position and to a collapsed position when the bottom members is moved to its inner position. A still further object of the invention is to provide in furniture of the type described a bottom member extension formed of foldable sections and having novel supporting means for the rear section of said extension.

To these and other ends, the invention consists of certain parts and combinations of parts, all of which will be hereinafter described: the novel features being pointed out in the appended claims.

In the drawings:

Fig. 1 is a view showing one of the sides or end frames removed with parts in section, the furniture being illustrated in the position it occupies when it acts as a davenport or seat;

Fig. 2 is a similar view showing the furniture adjusted in order to gain access to the receptacle beneath the removable bottom frame;

Fig. 3 is a fragmentary perspective view showing the manner in which the tracks for the bottom member are supported at their rear ends;

Fig. 4 is a view similar to Fig. 1 with parts in section, showing the bottom member adjusted to its outer position;

Fig. 5 is an enlarged fragmentary view showing the bottom member and its extension;

Fig. 6 is a fragmentary view showing a portion of the bottom member and its extension in plan and the connection of the latter to one side of the frame;

Fig. 7 is a fragmentary perspective view showing the manner in which the bottom

member extension is supported at its rear end;

Fig. 8 is a fragmentary view, partially in section, illustrating the track and the manner in which the rear end of the extension is supported; and

Fig. 9 is a vertical fragmentary section showing the connection of the bottom member and its extension with one side of the box frame.

In the illustrated embodiment of the invention, the frame of the furniture embodies a lower box frame comprising two longitudinally extending frame pieces 1 and 2 connected by transverse or side frame pieces 3 at a short distance from the ends of the longitudinally extending pieces 1 and 2. A bottom 4 closes this frame to provide a receptacle in which any suitable material may be contained. Upholstered sides 5 connect with this lower box frame and are connected with an upholstered back 6, which has its transverse bottom piece 7 spaced from the rear longitudinally extending member of the box frame to provide a chamber 8 or recess 80 beneath the upholstered back.

The transverse pieces 3, it will be noted, are spaced from the upholstered sides 5 so that chambers 9 are formed at each end of the box frame beyond said side pieces 3. 85 In these chambers are supported tracks for a movable bottom member 17. In this instance, attaching plates 10 are secured to the ends of the rear pieces 2 beyond the side pieces 3 and attaching plates 11 are secured 90 to the outer faces of the side pieces 3 adjacent the forward ends thereof, these attaching pieces 11 having offset portions 12 to which the forward ends of the tracks are secured. The tracks, in this instance, have horizontal 95 rear portions 13, inclined portions 14 leading upwardly from the rear portions and forward horizontal portions 15 in a higher plane than the horizontal portions 13.

On the tracks, supports 16 on the rear 100 ends of the movable bottom member 17 are mounted. Each of these supports, in this instance, carries two rollers 18 and 19 arranged respectively above and below a track, the upper roller travelling on the upper surface of the track and the lower roller being arranged to cooperate with the lower portion of the track to hold the support 16 to the track. In addition to the support 16, the movable bottom member 17 has a pair of 105 110

swinging supports 20, these supports being pivotally connected at 21 to the bottom member on the underside thereof about the middle of the latter and having their middle 5 ends pivoted at 22 to the brackets 12. Coil springs 23 are connected at 24 to the bottom member 17 preferably at the rear end of the latter and, in this instance, through the supports 16. The forward end of each 10 of these springs is connected at 25 to the swinging member 23 between the pivots 21 and 22 of the latter and, in this instance, nearer to the pivot 21. When the bottom member is in its outer position, as illustrated 15 in Fig. 4, these springs are untensioned, but, as the bottom member moves inwardly, the point 25 moves relatively to the point 24 and places each spring under tension so that, when the bottom member is in its inner 20 position, as illustrated in Fig. 1, the springs are tensioned in such a manner as to assist in the movement of the bottom member to its outer position. When the bottom member moves outwardly, the rollers 18 on the 25 support 16 are compelled to travel up the trackway 14 and the outer edge of the bottom member is caused to swing upwardly through the links 20. As a consequence, the weight of the bottom member acts against 30 the spring 17 as the supports 16 move upwardly on the inclined portions 14 of the trackway, so that, eventually, the weight of the bottom member will equal the pulling action of the springs 23 and the bottom 35 member will come to a neutral position shown in Fig. 2 where the interior of the receptacle beneath the bottom member will be exposed for access without fear of the bottom member moving in either direction. 40 The front edge of the bottom member may be supported in any suitable manner as by supports 26 which may be connected to the bottom member in any suitable manner. The foregoing parts are not claimed per se 45 herein as they are fully described and claimed in one or more of the following applications filed by me: Serial No. 753,743, filed December third, 1924; Serial No. 10,697, filed February twentieth, 1925; Serial No. 65,464, filed October twenty-eighth, 50 1925.

The feature of this invention is the novel construction of an extension for the bottom member for occupying the space between the 55 rear edge of the bottom member and the back when the bottom member is in its outer position. This extension, in this instance, embodies two sections pivotally connected one to the other, one of the sections being 60 pivotally connected to the bottom member. This last mentioned section embodies side pieces 27 pivotally connected at 28 to the rear cross piece 29 of the bottom member and connected by a longitudinal extending strap spring 30. This strap spring has transverse 65

strap springs 31 secured thereto and pivotally connected at one side to a rod 31^a secured to the transverse strap springs 32 of the bottom member 17 but having its ends free of the side pieces 27 and the cross piece 29. The other section of the extension embodies a longitudinal piece 33 and side pieces 34 forming a substantially U shaped member. The side pieces are pivoted at 35 to the side members 27 of the first mentioned 70 section and the transverse strap springs 36 of this last mentioned section are pivotally connected to a rod 37 which also extends through loops formed at the rear ends of the strap springs 31 of the first mentioned 75 extension section, the rod 37 having its ends free from the side pieces 34 and the side members 27 so that the sections may fold without producing any bending or distortion of the rod 37. 80

With the end in view of supporting the rear section of the extension so that it may move rearwardly and downwardly, two links 38 are preferably provided, these links being pivoted at 39 to the rear section of the extension at their upper ends and having their lower end pivoted at 40 to the plates 41 secured to the inner faces of the transverse piece 3 of the box frame. Also supporting the rear end of the rear section of the extension are two supports 42 each also pivoted at 39 to the rear section and being provided with shoulders or abutments 43, see Figs. 5 and 7, adapted to cooperate with lateral projections 44 on side members 34 of the U shaped frame of the rear extension section. The lower ends 45 of these members are adapted to rest on abutments 46 formed by cutting lugs from the plate 41 before mentioned, so that when the rear extension 90 is in operative position, the strain is taken off the links 38 and imposed between the shoulders 43 on the supports 42 and the lower ends 45 of said support. For the purpose of guiding each support 42 toward and 95 from an abutment 46, the support 42 has a curved surface 47 which travels on a pin 48 projecting from the plate 41. When the bottom member 17 moves inwardly, the links 32 swing rearwardly and downwardly while 100 the supports 42 travel rearwardly on the pins or abutments 48. This causes the rear end of the rear part of the extension to swing downwardly and the forward edge to swing upwardly whereby both sections of 105 the extension move into substantially parallel relation to vertical positions in the chamber beneath the upholstered back 6 as 110 illustrated in Fig. 1.

A flexible cover 49 is secured at 50 to the forward edge of the front member 17, extends rearwardly over the front member and over the extension, its rear free edge being secured at 51 to the upper surface 115 of the bottom piece 7 of the upholstered 120

back. Two upholstered cushions 52 and 53 may be provided, and a quilt 54 is secured to the uppersurface of the cushion or member 52 and is of a width to cover the cushion 5 or upholstered member 53, the quilt extending beyond the rear edge of the cushion 52 a sufficient distance to permit this coverage.

This quilt is folded in the manner illustrated in Fig. 1, when the cushion or seat 10 is used as a davenport and, when the furniture is used as a couch or bed, the quilt covers the upholstered member 53 as illustrated in Fig. 4. The covering 49 hereinbefore mentioned not only protects the undersurface of the upholstered cushions or members 52 and 53 from the action of the strap springs of the bottom member and its extension, but it serves to prevent dust or other particles passing downwardly into the 20 receptacle below the bottom member when the latter is in open position.

The operation of the invention will be understood from the foregoing but it may be summarized as follows: When the furniture is to be used as a seat or davenport, the parts are positioned as shown in Fig. 1. If access is desired to the compartment or receptacle below the bottom member, the bottom member is pulled forwardly, being assisted in this action by the spring 23, the upholstered member 53 first being swung to the position illustrated in dotted lines as shown in Fig. 1. Eventually a neutral position is reached as shown in Fig. 2, where the 35 action of the springs 23 on the bottom member is equal to the friction on the trackway and the weight of the bottom member and the parts carried thereby, so that the interior of the receptacle is open for access. If it is desired to provide a bed or couch, the bottom member is moved forwardly to the position shown in Fig. 1. During this time the two extension sections move to the horizontal position shown in Fig. 4, after which the 40 cushion 53 is placed thereon and the extension of the quilt 53 is thrown over said cushion, so that the parts appear as shown in Fig. 4. In moving the parts from the positions shown in Fig. 4 to the positions 45 shown in Fig. 1, the quilt extension is first thrown over the cushion 52 and then the cushion 53 is placed upon the cushion 52. The forward edge of the bottom member 1 is then lifted and pushed rearwardly and 50 travels down the trackway to the rearward horizontal portion 13. The bottom member extension during this time folds from the horizontal position shown in Fig. 4 to the vertical position shown in Fig. 1.

55 As the rear section of the extension is supported by swinging links pivoted at both ends and also by the supports 42 which are adapted to slide on the abutments 46, it is possible for the bottom member to swing 60 or move forwardly in order that the support

26 may engage the floor. This is important when the flooring is uneven for should the furniture frame rest on a higher surface than that to be engaged by the supports 26, and the rear end of the extension be held 70 against forward movement, then the support 26 would not engage the floor. In this invention, the supporting means for the rear extension section can move back and forth on the abutment 46. 75

What I claim as my invention and desire to secure by Letters Patent is:

1. In furniture, the combination with a frame, a receptacle arranged at the bottom of said frame, an upholstered back supported in fixed relation on the frame, the frame being provided with a chamber below the back, a bottom member having a length at least as long as the receptacle in the frame, and means for supporting the bottom member 80 to permit the same to be moved from an inner position where it acts as a seat, and a cover for the receptacle, to an outer position where it acts as a part of the bed bottom, of an extension for the bottom member embodying two sections hingedly connected together, one of the sections being hingedly connected to the bottom member near the rear edge of the latter and the rear section being of less length than the bottom member 85 so that the bottom member projects at each end beyond the ends of the rear section, and means causing the rear edge of the rear section to move rearwardly and downwardly into the receptacle and the pivotal connection between the sections to move upwardly in rear of the forward edge of the fixed back as the bottom member is moved to its inner position. 90

2. In furniture, the combination with a 105 frame, an upholstered back supported by the frame, the frame having a chamber beneath said back, a bottom member, and means for supporting said bottom member for movement from an inner position where the bottom member acts as a seat to an outer position where the bottom member acts as part of a bed bottom, of an extension for the bottom member to complete the bed bottom 110 when the bottom member is in its outer position, said extension embodying two hingedly connected sections, one of said sections being hingedly connected to the rear part of the bottom member, and a combined guiding and supporting means for guiding the rear edge of the rear section causing the latter to move rearwardly and downwardly as the bottom member is moved to its inner position so that the hinged connection between the sections may move upwardly and beneath the upholstered back, and causing also the rear section to move upwardly and forwardly as the bottom member is moved to its outer position, said combined guiding 115 and supporting means having a connection 120

125

130

with the rear section of the extension permitting the rear section to swing forwardly or backwardly independent of the guiding and supporting means, when the latter is at 5 its innermost position in order that the hinged connection between the two sections may swing into or out of the chamber under the back.

3. In furniture, the combination with a 10 frame, a bottom member, and means for supporting the bottom member for movement to an inner position where it acts as a seat to an outer position where it acts as part of a bed bottom, of an extension for the bottom member embodying two sections hinged- 15 ly connected one to the other and the inner one being hinged to the bottom member, a support pivotally connected to the rear section near the rear edge of the latter, means 20 for limiting the moving of said support in one direction, two abutments near the rear end of the support, one of the said abutments being curved, a device carried by the frame over which the curved abutment of 25 the support travels as the bottom member moves from an inner to an outer position, and an abutment on the frame with which the other abutment on the support engages when the bottom member is in its outer 30 position.

4. In furniture the combination with a 35 frame, a bottom member, and means for supporting the bottom member for movement to an inner position where it acts as a seat to an outer position where it acts as part of a bed bottom, of an extension for the bottom member embodying two sections hinged- 40 ly connected one to the other and the inner one being hinged to the bottom member, a support for the outer edge of the bottom member for engaging the surface on which the furniture rests, a combined guiding and supporting means for guiding the rear edge of the rear section, causing the latter to move 45 rearwardly and downwardly as the bottom member is moved to its inner position, so that the hinged connection between the sections may move upwardly, and causing the rear section to move upwardly and forwardly as the bottom member is moved to its outer 50 position, and an abutment with which said combined guiding and supporting means has a sliding connection when the bottom member is moved outwardly to permit the support at the outer edge of the bottom member to adapt itself to the surface on which the furniture rests.

5. In furniture the combination with a 60 frame, a bottom member, and means for supporting the bottom member for movement to an inner position where it acts as a seat to an outer position where it acts as part of a bed bottom, of an extension for the bottom member embodying two sections hinged- 65 connected one to the other and the inner one

being hinged to the bottom member, a link 70 pivotally connected to the rear section near the rear edge and also pivotally connected to the frame and causing the rear edge of the rear extension to move rearwardly and downwardly as the bottom member is moved to its inner position, an abutment on the frame, and means carried by said extension for engaging said abutment to support the extension when the bottom member is moved 75 to its outer position.

6. In furniture the combination with a 80 frame, a bottom member, and means for supporting the bottom member for movement to an inner position where it acts as a seat to an outer position where it acts as part of a bed bottom, of an extension for the bottom member embodying two sections hinged- 85 ly connected one to the other and the inner one being hinged to the bottom member, a link pivotally connected to the rear section near 90 the rear edge of the latter and also pivotally connected to the frame, a support mounted to turn on the axis of turning of the link, means limiting the movement in one direction of the support on its pivot, said support having a curved surface and an abutment, means on the frame with which said curved surface engages as the support swings, and an abutment on the frame with which 95 the abutment on the support may engage.

7. In furniture the combination with a 100 frame, a bottom member, and means for supporting the bottom member for movement to an inner position where it acts as a seat to an outer position where it acts as part of a bed bottom, of an extension for the bottom member embodying two sections hinged- 105 connected one to the other and the inner one being hinged to the bottom member, a link pivotally connected to the rear section near the rear edge of the latter and also pivotally connected to the frame below the extension, an abutment on the frame, and means carried by the frame for loosely engaging 110 the abutment when the bottom member is in its outer position in order to support the rear extension, said means having a lost motion connection with the rear section, so that the latter may swing relatively thereto while 115 the bottom member is being moved to and from its inner position.

8. In furniture, the combination with a 120 frame, a bottom member and means for supporting the bottom member so that the latter may move to an inner position and also to an outer position, of an extension for the bottom member comprising two sections pivotally connected, one of said sections being pivotally connected to the bottom member, 125 and two links pivoted to the frame below the extension when the latter is in inoperative position and pivotally connected to the rear section of the extension near the rear of the latter so that the rear edge of the rear 130

extension may move rearwardly and downwardly, and two supports for the extension each secured at its upper end to the rear section of the extension and each provided with 5 a curved surface, and means provided on the frame for engaging with said curved surfaces as the rear edge of the rear section of the extension moves to and from operative position and abutments on the frame with 10 which said supports engage when the bottom member is moved to its outer position.

9. In furniture, the combination with a frame provided with a back fixed relatively to the frame, a bottom member, means for 15 supporting said bottom member to permit it to move to an inner lower position and an outer higher position, of an extension for occupying the space between the bottom member and the back when the bottom member 20 is in its outer position, said extension comprising two members pivoted one to the other, one of said members being pivoted to the rear edge of the bottom member, means for supporting the rear edge of the extension 25 so that said rear edge may move rearwardly and downwardly to cause both sections of the extension to occupy vertical positions in the chamber beneath the back when the bottom member is moved to its inner or 30 lower position, and a flexible cover secured to said bottom member extending loosely over the extension and having its rear edge secured at the rear portion of said chamber in a position so that the two members of the 35 extension may fold into the chamber beneath the back without interfering with the secured rear edge of the cover.

10. In furniture, the combination with a frame, a bottom member, and means for supporting the bottom member for movement on the frame from an inner position to an outer position and vice versa, of an extension member embodying two sections pivotally connected one to the other, one of said 45 sections being pivotally connected to the bottom member, two supports secured to the rear section near the rear edge of the latter, each of said supports for the extension having a curved surface, means on the frame 50 for engaging with said curved surface during the movement of the curved supports, and means for guiding the rear edge of the rear section of the extension so that the latter moves rearwardly and downwardly when 55 the bottom member is moved to its inner position.

11. In furniture, the combination with a frame, a bottom member, and means for supporting the bottom member for movement on the frame from an inner position to an outer 60 position and vice versa, of an extension member embodying two sections pivotally

connected one to the other, one of said sections being pivotally connected to the bottom member, two supports for the rear section secured to the rear section near the rear edge of the latter each of said supports having a curved surface, means on the frame for engaging with said curved surface during the movement of the curved supports, 65 means for guiding the rear edge of the rear section of the extension so that the latter moves rearwardly and downwardly when the bottom member is moved to its inner position, and abutments on the frame for engagement by said supports when the bottom member is moved to its outer position.

12. In furniture, the combination with a frame having a fixed back and a chamber below the back, a bottom member having an inner position where it acts as a seat and an outer position where it acts as part of a bed bottom, and means for supporting the bed bottom for movement from its inner to its outer position or vice versa, of an extension 80 for the bottom member, when the latter is in its outer position embodying two hingedly connected sections, one of which is narrower than the other and is hinged to the bottom member near the rear edge of the latter and 85 has a width at greatest substantially equal to the distance between the upper surface of the bottom member and the forward lower edge of the chamber below the fixed back when said bottom member is in its inner 90 position, a link pivoted to the rear section near the rear edge of the latter and to the frame below the bottom member and causing the rear edge of the rear section to move 95 in rear of and below the position it occupies when the bottom member is in its outer position, so that the hinged connection between the sections may move upwardly into the chamber beneath the fixed back when the bottom member is moved to its inner position, and means for supporting the rear section in its horizontal position to prevent its 100 swinging on the link as a pivot when the bottom member is in its outer position.

13. In furniture, the combination with a frame, and a bottom member movable on the frame from an inner to an outer position and vice versa, of an extension for the bottom member embodying two sections each having side pieces pivoted to the side pieces of the other, the side pieces of one section being pivoted to the bottom member and both of said sections having transverse strap springs, and a pivot rod to which the transverse strap springs of both sections are pivoted, said rod having its ends free of the side pieces of the sections.
